UNITED STATES PATENT OFFICE.

ROBERT H. HAZELTINE, OF NEW YORK, N. Y.

FUEL TANK.

Application filed June 17, 1921. Serial No. 478,333.

To all whom it may concern:

Be it known that I, ROBERT H. HAZELTINE, a citizen of the United States, and a resident of the city of New York, in the county and State of New York, have invented an Improvement in Fuel Tanks, of which the following is a specification.

My invention relates to devices for elevating liquids from a low to a higher level and for discharging such elevated liquids by gravity to a device in which they are used and has particular application to such devices when used as fuel tanks in motor vehicles in which the main source of fuel supply is a tank located at a convenient low level and the fuel is raised to a higher level in order to be discharged by gravity to the carburetor.

In such devices it is desired to secure as nearly as possible a constant flow at constant pressure to the carburetor and it is of course desirable to provide a device which will operate with great certainty under widely varying conditions of load, throttle opening and variation of the vacuum by which the device is operated. It is also desirable to design the device so that it will have the minimum number of moving parts and that such parts will be rugged and simple of construction.

In the drawings, I have shown,

In Fig. 1, a sectional view of my improved device showing the primary control valve;

In Fig. 2, a section taken on the line 2—2 of Fig. 1;

In Fig. 3, a sectional view of the valve mechanism of the device; and

In Fig. 4, a sectional view showing the secondary control valve.

Referring to the drawings, it will be seen that my improved fuel tank comprises a plurality of fuel containers in the particular modification illustrated, two in number, each container having an associated valve mechanism. The containers may for convenience be called the primary and secondary containers and as will hereafter be shown, the valve mechanism for the secondary container depends for its operation upon the condition of the valve mechanism of the primary container, the arrangement being such that the primary container is called upon to perform most of the work of elevating and discharging liquid, the secondary container being called upon to provide a supplementary or equalizing supply during periods at

which the primary container is not discharging.

Referring to the drawings, 1 is the primary container, 2 is the secondary container. Each of said containers is provided with a float 3 and 4 which is connected by means of suitable linkage, comprising the hanger 5, lever 6, link 7 and bell crank 8, with the valve. Link 7 may be slotted as at 9, to permit a limited movement of the float without affecting the valve. Both of said containers are arranged to discharge into a common carburetor supply pipe 10, through valves 11 and 12. Each of the containers may be provided at any suitable place with an aperture 45 into which a funnel 46 and plug 47 are fitted for the purpose of priming when necessary.

The control valves are mounted upon a suitable cover 13 which tightly closes the containers 1 and 2 and may be conveniently arranged in a valve casing 14, suitably bored to take the piston valve 15 for the primary container and the piston valve 16 for the secondary container. Suitable connections are made in the valve casing, preferably immediately above the primary valve 15 for supplying the liquid and air to the containers and connecting the source of suction. Referring to Fig. 1, the pipe 17 is the fuel supply pipe which is branched to form two ports 18 and 19. The connection to atmosphere is made through apertures 20 and 21 and the connection to suction through pipe 22 which is branched to form two ports 23 and 24. The valve casing 14 contains passages connecting the two valves 15 and 16, 25 being a liquid supply passage which may be made to register with port 19 through port 32, 26 being an air supply passage which may be made to register with port 20, through port 31, and 27 being a suction passage which may be made to register with port 23 through port 29. The primary valve 15 contains primary suction passage 28, secondary suction passage 29, primary air passage 30, secondary air passage 31, secondary liquid passage 32, primary liquid passage 33. Secondary valve 16 contains the following apertures: suction 34, air 36, and liquid 37. An air port 35 is provided in the casing to register with aperture 36, as will be explained hereafter.

As will be clearly seen from Fig. 1, the valves are moved by bell crank 8 and may be adjusted by means of limit screws 38 and 39.

The operation of my improved device is as follows: Assuming the parts to be in the position shown in Fig. 1, the secondary container being assumed to be discharging at the time, it will be seen that the primary container which is shown in the figure is partly full of liquid, that the float 3 has reached the position at which it would begin to actuate the valve 15 and that the valve 15 is shown in a position such that the primary container is connected to suction through ports 28 and 24, that the air supply at port 21 is shut off by reason of the failure of ports 21 and 30 to register and that the fuel supply to the primary container is open through the registry of ports 18 and 33. Primary container 1 is therefore under vacuum with the air supply cut off and fuel being supplied to it. At this time, due to the position of valve 15, fuel is shut off from the secondary container by reason of the failure of ports 19 and 32 to register, air is being supplied to the secondary container by reason of the registry of ports 20 and 31 and suction is shut off from the secondary container by reason of the failure of ports 23 and 29 to register. As the level of the liquid in container 1 rises, the float actuates the valve 15 through the connecting mechanism to throw it to its extreme position towards the right of Fig. 1. This will cause ports 28 and 24 to fail to register, thus cutting off the suction from primary container 1, cause ports 23 and 29 to register, thus providing a passage for suction to the secondary container valve, will vent primary container 1 to atmosphere by the registering of ports 21 and 30, will cut off the air from the secondary valve by bringing ports 20 and 31 out of registry, will connect the liquid supply through ports 19 and 32 with the secondary valve and will shut off the liquid supply to the primary container by throwing ports 18 and 33 out of registry. When valve 15, therefore, is in the extreme right-hand position, the primary container is in the condition of having its suction and fuel shut off and being vented to the atmosphere.

The operation of the valve 16 of the secondary container is shown in Figs. 1 and 4. When the parts are in the position shown in Fig. 1 (the only connection to secondary container made through valve 15 at that time being the connection to atmosphere through ports 20 and 31) secondary control valve 16 will connect secondary container 2 with atmosphere through port 36 registering with passage 26, which as explained above, is connected at that time through valve 15 with the atmosphere. Thus when valves 15 and 16 are in the position shown in Figs. 1 and 3, secondary container 2 is discharging and open to the atmosphere. It will be understood that at this time, of course, the check valve 12 opens to permit the contents of con-

tainer 2 to flow into the discharge pipe 10.

When, however, the level in primary container 1 has risen to such an extent as to throw primary valve 15 to its right-hand position, primary container 1 commences to discharge, the container having been connected to atmosphere as described above and valve 11 being open to permit the liquid to flow into the discharge conduit 10, and by reason of the movement of valve 15 as explained above, atmosphere has been cut off from the secondary container and suction and liquid connected to it. Secondary container 2, therefore, will commence to fill under the influence of the suction and will continue to fill until the float 4 rises to move valve 16 to the left-hand position (see Fig. 4, upward in Fig. 3) if by that time primary container 1 has not discharged sufficiently to move valve 15 to its left-hand position. Assuming, therefore, that valve 15 is still in its left-hand position and float 4 of the secondary container 2 is moved upward, it will be seen that the movement of valve 16 will shut off the suction by the movement of port 34 with respect to passage 27, will vent the secondary container to atmosphere through passage 35, registering with port 36, and will shut off the liquid by moving port 37 out of registry with passage 25. In this condition both primary and secondary containers will discharge simultaneously, or if the level of the liquid in either container be higher than the other, that having the higher level will discharge until the levels are equalized.

In practice, as will be readily understood from the drawings and foregoing description, variation in level, except in cases of inordinate demand, is limited substantially to the lost motion provided in the links 7, as shown at 9 plus the necessary movement of the float to produce movement of the valves and therefore, if desired, the variation in level may be confined within very narrow limits. It will also be seen that without excessively varying the level of the liquid in the containers, the apparatus is such that large demands are readily met and the device is therefore particularly adapted for use under conditions in which wide variations of load, vacuum and fuel supply are met with.

While I have only shown one form of my invention, it will be obvious to those skilled in the art that many changes may be made therein without departing from the spirit of my invention, and I therefore do not intend to confine myself to the modification shown and described.

I claim:

1. In a device of the kind described, a plurality of containers discharging into a common outlet, a source of vacuum, a source of liquid supply, valve mechanism respon-

- sive to the liquid level in one of the containers for connecting said container either to vacuum and liquid supply, or to atmosphere, and valve mechanism operable independently of the first mentioned valve mechanism but responsive to the liquid level in another container and under the control of said first valve mechanism for connecting said other container either to vacuum and liquid supply or to atmosphere.
2. In a device of the kind described, a primary container, a secondary container, a source of vacuum, a source of liquid supply, a valve mechanism for said primary container and operative responsive to variations in liquid level in said primary container for connecting said container to liquid supply and vacuum or to atmosphere, and valve mechanism for said secondary container operable independently of said first mentioned valve mechanism but responsive to variations in liquid level in said primary container for connecting said secondary container to liquid supply and vacuum or atmosphere.
3. In a device of the kind described, a primary container, a secondary container, a source of vacuum, a source of liquid supply, a valve mechanism responsive to variations in liquid level in the primary container adapted to alternately vent the primary and secondary containers to atmosphere, and a valve mechanism responsive to variations in liquid level in the secondary container for venting the secondary container to atmosphere independently of said first mentioned valve mechanism.
4. In a device of the kind described, a primary container, a secondary container, a source of vacuum, a source of liquid supply, a valve mechanism responsive to variations in liquid level in the primary container

adapted to alternately vent the primary and secondary containers to atmosphere, and a valve mechanism responsive to variations in liquid level in the secondary container for venting the secondary container to atmosphere conjointly with and independently of said first mentioned valve mechanism.

5. In a device of the kind described, a plurality of containers connected to a common outlet, a common cover for said containers provided with a plurality of passages and valve seats, a valve slidable in each of said valve seats, a float in each container and controlling the reciprocation of each of said valves, a source of vacuum, and a source of supply, the before mentioned valves being provided with a plurality of ports so arranged as to register with the passages in said cover whereby variations in liquid level in the containers connect each of said containers either to liquid supply and vacuum or to atmosphere, one of said valves being dependent for its operation upon the liquid level in an adjacent container.

6. In a device of the kind described, a pair of containers discharging into a common outlet, a float in each of said containers, a liquid supply, a source of vacuum, an independent valve mechanism for one of said containers, and a valve mechanism for the other of said containers, said second named valve mechanism being controlled by said first mentioned valve mechanism, said valves being adapted to control the liquid supplied to the containers and adapted to be operated by independent floats in said containers.

In testimony whereof, I have signed my name to this specification this 14th day of June, 1921.

ROBERT H. HAZELTINE.
